Primary Examiner — Jae Liang*Assistant Examiner* — Ji Sun Yoon(74) *Attorney, Agent, or Firm* — Locke Lord LLP; Alicia J. Carroll(57) **CLAIM**

The ornamental design for a utensil for brewing and drinking, as shown and described.

DESCRIPTION

FIG. 1 is a perspective view of a utensil for brewing and drinking, where internal, unclaimed portions are visible through a transparent surface;

FIG. 2 is a side elevation view of the utensil for brewing and drinking of FIG. 1, where internal, unclaimed portions are visible through a transparent surface, and where the front side, back side, left side and right side views are identical; FIG. 3 is a top elevation view of the utensil for brewing and drinking of FIG. 1 where internal, unclaimed portions are visible through a transparent surface;

FIG. 4 is a bottom elevation view of the utensil for brewing and drinking of FIG. 1; and,

FIG. 5 is an enlarged version of FIG. 3, where FIG. 5 is shown 200% larger than FIG. 3 for sake of clarity.

(Continued)

The dashed broken lines in the drawings depict portions of the utensil for brewing and drinking that form no part of the claimed design.

1 Claim, 4 Drawing Sheets
